D. COOK.

WIRE ROPE CARRIAGE.

APPLICATION FILED OCT. 17, 1919.

1,343,434.

Patented June 15, 1920.

UNITED STATES PATENT OFFICE.

DAVID COOK, OF LYNN VALLEY, BRITISH COLUMBIA, CANADA.

WIRE-ROPE CARRIAGE.

1,343,434.

Specification of Letters Patent. Patented June 15, 1920.

Application filed October 17, 1919. Serial No. 331,318.

To all whom it may concern:

Be it known that I, DAVID COOK, a citizen of the Dominion of Canada, residing at Lynn Valley, in the Province of British Columbia, Canada, have invented certain new and useful Improvements in Wire-Rope Carriages, of which the following is a specification.

This invention relates to an overhead carriage of that class which is designed to travel on a wire rope track or standing line for the conveyance of shingle bolts or the like from the woods to the place of transportation.

The invention is particularly described in the following specification, reference being made to the drawings by which it is accompanied, in which:

Figure 1 is a side elevation of the carriage and the track rope stops with portions of the nearer plates removed.

Fig. 2 is an end elevation looking in the direction of the arrow 2, and

Fig. 3, an enlarged detail of the load lifting drum gear and its sustaining pawl.

Fig. 4 is a detail perspective view of the pawl device hereinafter specifically referred to.

In these drawings 2 represents the frame of the carriage which is carried on the track rope 4 by grooved sheaves 3 mounted in the frame, and 5 are guard sheaves beneath the rope preventing displacement of the carriage on the track. The track rope 4 is suspended in any suitable manner, where required through the woods, at a convenient height above the ground level, and the carriage 2 is drawn along that track rope by a hauling line 6, either in the direction of the arrow A toward the in-station, where the hauling engine is located, or in the direction of the arrow B toward the out-station, the rope passing through suitable guide pulleys around the circuit and back to the drum of the donkey engine.

This hauling rope 6 passes over guide pulleys 7 in the lower part of the carriage at each end, and between these guide pulleys passes around sheaves 8 and 9 mounted one above the other on the carriage.

On the shafts 10 and 11 of the sheaves 8 and 9 are secured pinions 12 and 13, the teeth of which mesh with those of an inside gear 14 secured on a drum 15 rotatably mounted between the side plates of the carriage. To this drum 15 is secured one end

of a load lifting line 16, the free end of which has a hook 17 to which the load of shingle bolts or the like is connected to be lifted to and lowered from the carriage. 60

This load lifting mechanism, represented by the sheaves 8 and 9 and drum 15, is held against lifting or lowering movement by a pawl 18 mounted on the carriage at 21, the free end of which pawl is laterally turned 65 to engage the teeth of the gear wheel 14 and the pawl is counterweighted to normally hold it in such engagement.

The end of the pawl 18 is produced beyond its pivot 21 and is upwardly angled, 70 as at 22, to project beyond the adjacent end of the carriage, so that when the carriage approaches the desired limit of its outward movement it will engage a stop 35 secured to the track line 4 and the pawl 18 will be 75 withdrawn from engagement with the teeth of the drum gear 14.

To enable release of this pawl 18 to be effected from the opposite end of the carriage, that is, at the desired limit of its 80 movement at the in-station, a lever 19 is pivotally mounted intermediate of its ends adjacent the other end of the carriage, one end of which lever is bent to project beyond the carriage and the other end is connected 85 by a rod 20 to the upwardly turned end of the release pawl 18.

The stop at the in-station end of the track line 4, where the donkey engine is located, comprises an upper clamp bar 25 secured to 90 the frame of the stop and a lower clamp bar 24 which is vertically movable to and from the fixed bar 25 to clamp the track rope 4 between them. This clamping movement is actuated by the eccentric cams 23 mounted 95 in the side frames to be rockable inward toward one another to effect the clamping, and outward to release it. A lever 26 extends from one of these cams, while to the other is secured, intermediate of its ends, 100 a lever 28, one end of which lever 28 is connected by a link 27 to the middle of the lever 26.

Thus, when the free end of the lever 26 is drawn down by a line 29 connected to it, 105 the cam 23 to which it is secured, is partially rotated to clamp the rope 4 and through the link 27 the same movement is imparted to one end of the lever 28 and rotates the other eccentric cam through the 110 same angular amount in the opposite direction to effect the clamping. Again, if the

lever 28 is drawn down by the line 30 connected to its free end, its eccentric cam 23 is rotated to effect release of the clamp and the upward movement of the opposite end 5 of that lever lifts the lever 26 to effect release of the other eccentric cam. The frame may thus be conveniently clamped or released as required.

10 The stop member 31 is secured to the side frames of the clamp to project forward to engage the end of the lever 19 of the carriage. The frames of the stop may also conveniently carry a sheave 32 over which the hauling rope 6 will pass.

15 Toward the outer end of the track rope 4 is secured another stop having a similar clamping and releasing means operable with lines from the ground level, but as this stop may require to be frequently moved to different positions on the track as the place of the cutting changes, its carriage 33 is mounted on sheaves 34 to run on the track rope 4. The underside of these sheaves 34 project slightly below the underside of the 25 upper clamp member 25, so that when the clamp is released the carriage is free to move without frictional contact of the clamp bar with the track rope.

20 The stop 35 of this frame projects from the end which is toward the carriage to engage the produced end 22 of the pawl 18 and release that pawl from engagement with the teeth of the drum gear 14.

25 Pivoted on the end of this stop frame 33 to project beyond the face of the stop 35 is a latch 36 adapted to engage and retain a hold of a pin 37 mounted on the adjacent end of the movable carriage 2, so that when the carriage engages the stop 35 it will be 30 retained there by the latch. The pin 37, which the latch engages, is rotatably mounted in the frame and has a projection 38 from its underside that when the pin is partially rotated will lift the end of the latch 45 36 from retaining engagement.

35 Rotation of the pin 37 is coöperative with approach of the load lifting hook 17 to the underside of the carriage 2 by means of an enlargement 39 on the line 16 adjacent its 40 connection to the hook, which enlargement engages the underside of a bell crank lever 40 pivotally mounted in the frame 2, the other end of which lever is connected by a rod 41 to a short lever 42 downwardly projecting from the pin 37, so that coincident with the lift of the load to the carriage, the carriage is released from the retaining latch 36.

45 In use, assume the carriage 2 as moving outward in the direction of the arrow B, the drum 15 being latched with the load hook 17 drawn up to the carriage; the drum being latched, the hauling rope is practically connected to the carriage by its passage 60 around the non-rotating sheaves 8 and 9,

and the carriage may be drawn along the track rope 4 by the hauling line 6 in the direction of the arrow B. When the end 22 of the pawl 18 engages the stop 35 at the place of loading or out-station, the pawl is 70 withdrawn from engagement with the teeth of the gear 14 and the drum 15 is free to rotate and simultaneously the latch 36 engages the pin 37 to retain the carriage against backward movement on the track 75 rope.

80 Further movement of the hauling rope 6 rotates the sheaves 8 and 9 to lower the load block 17 to the ground level. Thereafter, the load is connected and the hauling rope 6 is drawn in the opposite direction, as indicated by the arrow A, which movement, the carriage being retained by the latch 36 against endwise movement on the track, rotates the sheaves 8 and 9 and the drum 15 85 to lift the load to the carriage. As soon as the enlargement 39 engages the bell crank lever 40 the pin 37 is partially rotated to release the latch 36 and set the carriage free, and as the end 22 of the pawl lever 90 moves away from the stop 35 the pawl 18 assumes its normal position of engagement with the teeth of the gear wheel 14 and the load is retained adjacent the carriage 2 and clear of the ground as that carriage moves 95 along the track to the in-station where the load is to be deposited. On arrival at that station the projecting end of the lever 19 encounters the stop 31 and the pawl 18 is moved to release the drum 15, when the load 100 is free to be lowered to the ground, the rope 6 being paid out as required. The lowering movement will tend to hold the carriage against the stop 31.

Having now particularly described my 105 invention, I hereby declare that what I claim as new and desire to be protected in by Letters Patent, is:

110 1. A carriage for an overhead track, comprising the combination with a suitable frame having sheaves adapted to run on an overhead track, a drum rotatably mounted in the frame to which drum one end of a load sustaining line is connected, means for rotating the drum by the hauling rope from 115 the donkey engine, said means comprising a driving sheave around which the hauling rope is passed, a pinion secured to rotate with the driving sheave, the teeth of which pinion mesh with those of a gear wheel secured to rotate with the drum, means for normally holding the load sustaining drum against rotation in either direction whereby the carriage may be drawn in either direction along the track by the hauling rope, 120 means for holding the carriage against endwise movement on the track at the limit of its desired outward movement, means co-operative with attainment of the carriage to its limit of outward movement for re- 125 130

leasing the drum holding means whereby movement of the hauling rope may rotate the drum to lower or raise the load, means coöperative with elevation of the load to ward the carriage for releasing the carriage from the stop whereby the carriage is free to be drawn along the track by the hauling rope and the drum is again locked.

2. A carriage for an overhead track, comprising the combination with a suitable frame having sheaves adapted to run on an overhead track, a drum rotatably mounted in the frame to which drum one end of a load sustaining line is connected, means for 10 rotating the drum by the hauling rope from the donkey engine, said means comprising sheaves around which the hauling rope is passed before proceeding to the end of the line and returning to a drum of the hauling engine, pinions secured to rotate with the driving sheaves, the teeth of which pinions mesh with those of a gear wheel secured to rotate with the drum, means for normally holding the load elevating and 20 lowering drum against rotation whereby the carriage may be drawn along the track in either direction by the hauling rope, stops preventing movement of the carriage beyond a desired limit toward either end of 25 the track, means for holding the carriage to the outer limiting stop, means coöperative with attainment of the carriage at either limiting stop for releasing the drum holding means, whereby movement of the hauling rope may rotate the drum to lower or 30 raise the load, and means coöperative with elevation of the load toward the carriage for releasing the carriage holding means whereby the carriage is free to be drawn along the track by the hauling rope and the drum is again locked.

3. A carriage for an overhead track, comprising the combination with a suitable frame having sheaves adapted to run on an overhead track, guide sheaves at each end of the carriage over which the hauling rope from a drum of the donkey engine passes, two driving sheaves mounted one above the other intermediate of the guide sheaves 45 around which driving sheaves the hauling rope passes before proceeding over the other guide sheave and to the other end of the track to return to a drum of the donkey, a pinion secured to each driving sheave to rotate with it, the teeth of which pinions mesh with those of an internal gear secured to a load sustaining drum rotatably mounted in the frame of the carriage to which drum one end of a load sustaining line is connected 50 having a load hook at the other end, a stop removably secured to the track at the desired limit of the inward and out-

ward movement of the carriage, means normally preventing rotation of the load sustaining drum whereby the carriage 65 may be drawn along the hauling rope in either direction, means operative by attainment of the carriage to the stop at either limit for releasing the drum whereby movement of the hauling rope effects rotation of 70 the drum to raise or lower the load, means for automatically holding the carriage against the stop at the outer limit of its movement on the track rope, and means operative by elevation of the load hook toward the carriage for releasing the carriage 75 from the stop.

4. A carriage for an overhead track, comprising the combination with a suitable frame having sheaves adapted to run on an overhead track and to retain it thereon, guide sheaves at each end of the carriage over which the hauling rope from a drum of the donkey engine passes, two driving sheaves mounted one above the other in the 80 frame intermediate of the guide sheaves around which driving sheaves the hauling rope passes before proceeding over the other guide sheaves to the other end of the track to return to a drum of the donkey, a pinion secured to each driving sheave to rotate with it, the teeth of which pinions mesh with those of an internal gear secured to a load sustaining drum rotatably mounted in the frame of the carriage, a load line connected to the drum, a stop removably secured to the track at the desired limit of 85 the inward and outward movement of the carriage, a pawl weighted to normally engage the teeth of the gear wheel of the 90 drum, one end of which pawl is produced beyond its pivot to project beyond the adjacent end of the carriage and is bent upward to engage the stop at the outer limit of the carriage movement on the track, the 95 other end of which pawl is upwardly turned and connected by a rod to one end of a bell crank lever, the other end of which projects beyond the other end of the carriage to engage the in-stop, a latch pivotally mounted 100 on the out-stop and adapted to engage a pin rotatably mounted on the adjacent end of the carriage, which pin has a projection from one side adapted to lift the latch from engagement with the pin when the same 105 is partially rotated, and an arm projecting from the pin and connected by a rod to one end of a bell crank mounted in the lower part of the carriage, the other end of which crank projects in the path of an enlargement secured to the load line.

In testimony whereof I affix my signature.

DAVID COOK.
